UNITED STATES PATENT OFFICE.

JOHN C. JOHNSON, OF ST. LOUIS, MISSOURI.

MEANS FOR USE IN SEALING FIBER BOXES, CARTONS, AND THE LIKE.

1,142,813.

Specification of Letters Patent. Patented June 15, 1915.

Application filed August 24, 1914. Serial No. 858,227.

To all whom it may concern:

Be it known that I, JOHN C. JOHNSON, a citizen of the United States, residing at the city of St. Louis, State of Missouri, have invented certain new and useful Means for Use in Sealing Fiber Boxes, Cartons, and the like, of which the following is a specification, reference being had to the accompanying drawings, forming a part thereof.

10 This invention relates to certain new and useful means especially adapted for use in sealing boxes, cartons, and the like of fiber-board, heavy card or paste-board, corrugated-board, and analogous material.

15 As is well known, boxes and cartons of the kind stated, and particularly such boxes or cartons of the larger sizes designed specially to contain, and as shipping receptacles or containers for, heavy goods, such, for instance, as bars of soap, are generally supplied by the manufacturer to the consumer in a knocked-down, folded, flat condition. When the box or carton is to be used, the same is opened up or unfolded and assumes 20 usually a rectangular form, the loose flaps on each of the opposite sides of the box being folded in upon one another ready to be sealed or secured together, which is largely accomplished by means of glue or other adhesive material applied to the matching or contacting faces of the several flaps. In so sealing the flaps of the box or carton, the practice has heretofore generally been, so far as I am aware, to first apply the glue or 25 other adhesive material to the flaps on one side of the box and then allow the box or carton to stand or rest, with its said side under-most, on a conveyer or other place of support a sufficient length of time to permit 30 the glue or other adhesive material to set and harden, the contents of the box or carton serving in this operation as a weight to hold or maintain the flaps in proper sealing position. Afterward glue or other adhesive 35 material is applied to the flaps on the other or opposite side of the box, the box over-turned, and the box then again allowed to stand or rest, but with its said other side now under-most, on the place of support a 40 sufficient and equal length of time to permit the glue or other adhesive material to set and harden, the contents of the box again in this second operation serving as a weight to hold or maintain the said second set of 45 flaps in sealing position. Such repeated 50

operations, it will be evident, consume considerable time.

Hence the principal object of my present invention is to provide means whereby the sets of flaps on both the opposite sides of 60 the box may be simultaneously firmly held and maintained in sealing position during the setting and hardening of the glue or other adhesive material, with the result that the two sets of flaps of the box may be completely sealed in one operation and in far less time than has heretofore been required for such purpose.

With the above and other objects in view, my present invention resides in the provision of a pair of coöperating tray-like members adapted to yieldingly fit and engage the box or carton at both of its opposite sides, the box or carton being in unfolded condition with its flaps inturned 70 ready for sealing and glue or other adhesive material being applied thereto, and to be releasably locked or clamped together with the box firmly held therebetween with its flaps in sealing position, the said members 75 holding or maintaining the flaps in proper sealing position during the setting and hardening of the glue or other adhesive material, and in certain novel features of form, construction, arrangement, and combination 80 of parts, all as will hereinafter be described 85 and afterward pointed out in the claims.

In the accompanying drawings, which show the preferred embodiment of my invention, Figure 1 is a side elevational view 90 of a pair of box-sealing members embodying my invention, the same being shown in operative locked position with a box being sealed therebetween; Fig. 2 is a top plan view of the same, partly broken away; Fig. 95 3 is a longitudinal vertical sectional view through the same on the line 3—3, Fig. 2; Fig. 4 is a top plan view of a slightly modified form of box-sealing member embodying my invention; Fig. 5 is a longitudinal sectional view on the line 5—5, Fig. 4, a pair 100 of said slightly modified box-sealing members being shown in coöperative position with a box (shown in dotted lines) being sealed therebetween; Fig. 6 is a transverse 105 sectional view on the line 6—6, Fig. 4, a pair of said slightly modified box-sealing members being also shown in coöperative position with a box (likewise shown in dotted lines) being sealed therebetween; and Fig. 110

7 is a fragmentary sectional view on the line 7-7, Fig. 2.

Referring to said drawings, in which like reference characters refer to like parts throughout the several views, 1 and 2 indicate the coöperating box-sealing members as entireties, each of said members, as will be seen, having the form substantially of a preferably rectangular shallow tray. Since 10 these members 1 and 2 are substantially alike in form, size, and construction, member 1 only will be here specifically described, the description thereof and reference characters applied thereto being equally applicable 15 to its coöperating member 2.

Member 1, which is of suitable size to correspond with and tightly fit exteriorly the particular size of box to be sealed, includes a preferably rectangular frame made up of 20 or comprising longitudinal members 3-3' and cross or transverse members 4-4' suitably fixed together at their meeting ends, members 3-3' and 4-4' being of suitable material and preferably curved or rounded, 25 as at *c*, on their inner faces, so that, when members 1 and 2 are being operatively placed upon a box to be sealed, the same will direct and force the flaps of the box inwardly into sealing position. Fixed to and 30 strengthening said frame at its corners are suitable preferably metallic angle members or brackets 5. Fixed at or adjacent their ends to, and upon one outer side face of, preferably longitudinal members 3-3' of 35 said frame, are cross members or outer bottom sections 6-6' also of any suitable material, members 6-6' being spaced apart preferably centrally of said frame to provide a space or slot, as at 7, therebetween, as seen 40 particularly in Fig. 1. Fitting flatwise within said frame formed of said members 3-3' and 4-4', and having a size preferably somewhat less than the interior area of said frame, is a preferably flat rectangular member or inner bottom section 8. Fixed transversely, and on the outer face, of inner bottom member 8, is a cross-piece 9 fitting 45 loosely in the said space or slot 7 between said fixed outer bottom sections 6-6', as seen clearly in Fig. 3, cross-piece 9 being 50 adapted to not only serve as a guide for inner bottom 8 in its yielding movements relatively to said fixed outer bottom members 6-6', but to also prevent lateral movement 55 of the same relatively thereto. On its outer face, cross-piece 9 is preferably recessed throughout its length, as at 10, and disposed lengthwise in said recess and fixed to said cross-piece 9, is a preferably metallic strap 60 11 adapted to securely hold inner bottom 8 in proper operative relation to said frame and its said outer bottom sections 6-6', strap 11 at its ends being bent inwardly and then outwardly to normally flatwise bear upon said 65 longitudinal frame members 3-3', as seen

clearly in Figs. 1 and 2. Interposed between each of said fixed outer bottom sections 6-6' and said inner bottom member 8, are leaf or flat springs 12-12', these springs being preferably fixed centrally thereof to said inner bottom member 8 and at their ends bearing yieldingly upon said outer fixed bottom sections 6-6', respectively. Also preferably interposed and suitably secured between said fixed outer bottom sections 6-6' and said inner bottom 8, are auxiliary yielding members in the form of coiled springs 13 adapted to co-act with said springs 12-12' in yieldingly holding said inner bottom 8 flatwise away from said fixed outer bottom sections 6-6' with said strap 11 engaging flatwise at its opposite ends with said longitudinal members 3-3' of said frame. It will be observed by reference particularly to Fig. 3 that inner bottom 8 is somewhat 85 throughout its margin spaced inwardly away from said frame members 3-3' and 4-4', so as to provide an interior space therebetween and said frame, as at 14, for the corners and edges of the box being sealed. 90 Fixed to, and on the inner face of each of, said cross members 4-4' of member 1, are hinged normally downwardly disposed (reference being had to Figs. 1 and 3) preferably metallic strips or elongated plates 95 15-15', respectively, and mounted upon said plates or strips are spring-pressed clamping members 16-16', respectively. Fixed to, and on the inner face of each of, said cross members 4-4' of member 2 in coöperative 100 position relatively to said strips or plates 15-15', are upwardly disposed (reference being again had to Figs. 1 and 3) preferably metallic strips or elongated plates 17-17', respectively, which are provided on their outer face with longitudinally disposed rows 105 of teeth 18-18', respectively, with which teeth said clamping members 16-16' are adapted to releasably engage when said members 1 and 2 are in operative position 110 with a box therebetween to detachably fasten 115 said members together.

In use or operation, a box B in unfolded condition with its flaps *a*-*a'* and *b*-*b'* in-turned for sealing and with glue or other adhesive material applied thereto, is set 120 within tray-member 2. Tray-member 1 is then placed upon the opposite side or end of the box, all as shown especially in Fig. 3, when, proper pressure being applied, clamping members 16-16' will be forced into engagement with said teeth 18-18' against the tension of said springs 12-12' and 13, said springs being compressed and said inner bottoms 8 of said members oppositely 125 flatwise yielding outwardly when said clamping members are being forced into locking engagement with said teeth. Members 1 and 2 being so locked or clamped together with box B therebetween, it will be 130

seen that the two sets of flaps of the box are firmly held together in proper, accurate sealing position, the said flaps being prevented from slipping or otherwise projecting over the sides or ends of the box. The box B with said members 1 and 2 locked thereupon is now permitted to rest on a suitable place of support to allow the glue or other adhesive material applied to said flaps to set and harden, and it will be obvious that, the sets of flaps on both opposite sides of the box being simultaneously held in proper sealing position, approximately just half the length or period of time for sealing is now consumed through the use of my invention than that which has heretofore been required, so far as I am aware. The box having been permitted to stand the required length of time, members 1 and 2 are further slightly yieldingly forced together, clamping members 16 and 16' disengaged from said teeth 18-18', and members 1 and 2 then easily removed from around the box, when the box, with its contents sealed therein, is ready for storage, shipment, or other desired purpose. Members 1 and 2 being removed from about the box, clamping members 16-16' and their said supporting plates 15-15', being preferably hinged, as described, on said member 1, may now be swung to project within the area of the frame of said member, member 2 superposed on member 1, and said members then conveniently stored away or moved from place to place about a plant, factory, or the like.

The modified form of my invention shown particularly in Figs. 4, 5, and 6 is greatly similar to the form of my invention hereinbefore described and shown in Figs. 1, 2, and 3, the principal difference being that the tray-like members of this form of my invention, instead of having an inner yielding bottom in one integral piece, are each provided with an inner bottom formed of separate sections separately yieldable, so as to provide for elevations or depressions in the flaps of the box being sealed due to, or caused by, elevations or depressions in the packed contents of the box.

Reference being had particularly to Figs. 4, 5, and 6 showing this modified form of my invention, the tray-like members 19 and 20 each likewise include a preferably rectangular frame formed of longitudinal members 21-21' and cross or transverse members 22-22'. Extending preferably longitudinally of the frame and adjacent its said longitudinal members 21-21', are outer bottom sections 23-23' fixed at their ends to said frame cross members 22-22'. Also extending preferably longitudinally of the frame adjacent said fixed outer bottom sections 23-23', are preferably metallic bars 24-24' also suitably fixed at their ends to

said frame cross members 22-22'. Loosely fitting on each of said bars, but prevented from sidewise or lateral movement on said bars by means of small annular portions or rings 25 integral with, or otherwise fixed to, said bars, are staples or the like 26, of which there are preferably four in number arranged in pairs on said bars, as seen particularly in Figs. 4 and 6. Lying within said frame formed of said members 21-21' and 22-22', is an inner bottom formed of sections or members in the form preferably of flat boards 27-27' and 28-28', each of said sections being fixedly engaged by a staple 26 and thereby swingably held in proper operative relation to the fixed outer bottom of the frame. Also extending longitudinally of said frame intermediate said bars 24-24' and also fixed at its ends to said frame cross members 22-22', is a central outer bottom section 29, and interposed between said outer bottom section 29 and said inner bottom sections 27-27' and 28-28' are pairs of preferably flat or leaf springs 30-30' and 31-31' each fixed preferably centrally to said outer bottom section 29, said pair of springs 30-30' yieldingly engaging at its ends with said pair of inner bottom sections 27-27' and said pair of springs 31-31' yieldingly bearing at its ends upon said other pair of inner bottom sections 28-28'. Also interposed between said outer bottom sections 23-23' and 29 and said inner bottom sections 27-27' and 28-28' are auxiliary yielding members in the form of coiled springs 32 adapted with said pairs of leaf springs to yieldingly hold said inner bottom sections away from said fixed outer bottom sections. The use and operation of this form of my invention with its tray-like members 19 and 20 is substantially similar to that of the form of my invention with its tray-like members 1 and 2, but it will be evident that, due to the sectional form of their inner yielding bottoms, the inner bottoms thereof will variously yield to accommodate depressions or elevations in the flaps of the box on members 1 and 2 being forced together into cooperative relation.

I am aware that changes in the form, construction, arrangement, and combination of the several parts of my new box-sealing means may be made and substituted for those herein shown and described without departing from the nature and principle of my invention.

Having thus described my invention, what I claim and desire to secure by Letters Patent is:

1. In a device of the kind described, a pair of coöperating tray-like members adapted to fit a box on opposite sides thereof and when engaging a box being oppositely disposed relatively to each other, each

of said members including a frame, an outer fixed bottom section on said frame, and an inner yieldable bottom section within said frame, and releasable means for detachably 5 fastening said members together in operative position with a box therebetween; substantially as described.

2. In a device of the kind described, a 10 pair of coöperating tray-like members adapted to fit a box on opposite sides thereof and when engaging a box being oppositely disposed relatively to each other, each of said members including a frame, an outer fixed bottom section on said frame, an inner 15 bottom section within said frame, said inner bottom section being flatwise yieldable relative to said outer bottom section, and means for holding said inner bottom section in operative relation to said outer bottom section, and releasable means for detachably 20 fastening said members together in operative position with a box therebetween; substantially as described.

3. In a device of the kind described, a 25 pair of coöperating tray-like members adapted to fit a box on opposite sides thereof and when engaging a box being oppositely disposed relatively to each other, each of said members including a frame, an outer fixed bottom section on said frame, an inner bottom section within said frame flatwise disposed relatively to said fixed outer bottom section, means for holding said inner bottom section in operative relation to 30 said outer bottom section, and yielding members interposed between said outer and inner bottom sections, and releasable means for detachably fastening said tray-like members together in operative position with a box 35 therebetween; substantially as described.

4. In a device of the kind described, a 40 pair of coöperating tray-like members adapted to fit a box on opposite sides thereof and when engaging a box being oppositely disposed relatively to each other, each of said members including a frame, spaced-apart outer bottom sections fixed on said frame, an inner bottom section within said frame, a cross-piece on said inner bottom 45 section loosely fitting between said outer fixed bottom sections, a fixed strap on said cross-piece normally engaging at its ends with said frame, and springs interposed between said fixed outer bottom sections and 50 said inner bottom section, and releasable means for detachably fastening said members together in operative position with a box therebetween; substantially as described.

5. In a device of the kind described, a 55 pair of coöperating tray-like members

adapted to fit a box on opposite sides thereof and when engaging a box being oppositely disposed relatively to each other, each of said members comprising a frame having a fixed outer bottom and a yieldable inner 65 bottom, and co-acting clamping members on said frames adapted to detachably fasten said tray-like members together in operative position with a box therebetween; substantially as described. 70

6. In a device of the kind described, a 75 pair of coöperating tray-like members adapted to fit a box on opposite sides thereof and when engaging a box being oppositely disposed relatively to each other, each of said members comprising a frame having a fixed outer bottom and a yieldable inner bottom, a plate on one of said members, said plate being provided with a row of teeth, and a clamping member on the other of said 80 tray-like members adapted to releasably engage with said teeth to detachably fasten said tray-like members together in operative position with a box therebetween; substantially as described. 85

7. In a device of the kind described, a 90 pair of coöperating tray-like members adapted to fit a box on opposite sides thereof and when engaging a box being oppositely disposed relatively to each other, each of 95 said members comprising a frame having a fixed outer bottom and a yieldable inner bottom, a plate on one of said members, said plate being provided with a row of teeth, and a clamping member pivotally mounted 100 on the other of said tray-like members, said clamping-member being adapted to releasably engage with said teeth when said tray-like members are in operative position with a box therebetween to detachably fasten said 100 tray-like members together; substantially as described.

8. In a device of the kind described, a 105 pair of coöperating tray-like frames adapted to fit a box on opposite sides thereof and when engaging a box being oppositely disposed relatively to each other, one of said frames being provided interiorly with a flatwise yieldable bottom, and releasable means for detachably fastening said members together in operative position with a box therebetween; substantially as described. 110

In testimony whereof, I have signed my name to this specification, in the presence 115 of two subscribing witnesses.

JOHN C. JOHNSON.
